Primary Examiner — Wan Laymon*(74) Attorney, Agent, or Firm* — Dunlap Bennett & Ludwig PLLC(57) **CLAIM**

The ornamental design for an orthodontic alignment device, as shown and described.

DESCRIPTION

FIG. 1 is a perspective view of an orthodontic alignment device, showing my new design;
FIG. 2 is a left elevation view thereof, the right elevation view being a mirror image thereof;
FIG. 3 is a front elevation view thereof;
FIG. 4 is a rear elevation view thereof;
FIG. 5 is a top plan view thereof, the bottom plan view being a mirror image thereof; and,
FIG. 6 is a perspective view of an orthodontic alignment device, showing my new design, shown in use.
The evenly-sized broken lines depict portions of the orthodontic alignment device that form no part of the claimed design. The unevenly-sized broken lines consisting of dash-dot-dash lines in the drawings depict the boundary of the claimed invention and it is understood that the claim extends to the boundary that forms no part of the claimed design.
